US00D838280S

(12) **United States Design Patent** (10) Patent No.: **US D838,280 S**
(45) Date of Patent: ** Jan. 15, 2019

(54) **VEHICLE INSTRUMENT PANEL DISPLAY SCREEN WITH GRAPHICAL USER INTERFACE**

(71) Applicant: **Faraday & Future Inc.**, Gardena, CA (US)

(72) Inventors: **Matthew Joseph Coburn**, Milford, MI (US); **Shuo Yuan**, Redondo Beach, CA (US); **Rei Watanabe**, Gardena, CA (US); **Christian Eckert**, Los Angeles, CA (US)

(73) Assignee: **FARADAY & FUTURE INC.**, Gardena, CA (US)

(**) Term: **15 Years**

(21) Appl. No.: **29/589,634**

(22) Filed: **Jan. 3, 2017**

(51) LOC (11) Cl. **14-04**

(52) U.S. Cl.

USPC **D14/485**

(57) **CLAIM**

The ornamental design for a vehicle instrument panel display screen with graphical user interface, as shown and described.

DESCRIPTION

The sole FIGURE is a front view of a vehicle instrument panel display screen with graphical user interface showing our new design.

The dash-dash broken lines illustrate environmental structure of the vehicle and form no part of the claimed design.

1 Claim, 1 Drawing Sheet
